Patented Nov. 18, 1919.

2 SHEETS—SHEET 2.

UNITED STATES PATENT OFFICE.

CYRUS S. OLDRYD, OF CINCINNATI, OHIO.

MINING AND QUARRYING MACHINE.

1,321,840.

Specification of Letters Patent. Patented Nov. 18, 1919.

Application filed August 17, 1915, Serial No. 45,923. Renewed November 1, 1918. Serial No. 260,722.

To all whom it may concern:

Be it known that I, CYRUS S. OLDRYD, a citizen of the United States, residing at Cincinnati, in the county of Hamilton and State of Ohio, have invented a new and useful Improvement in Mining and Quarrying Machines, of which the following is a specification, reference being had to the accompanying drawing.

10 My invention relates particularly to machines used for under-cutting walls in mines and quarries, such machines being usually placed adjacent a wall in a mine entry or room and moved toward or along such wall 15 to cause a rotary cutting device projecting forward from the machine to cut into the wall to prepare a portion thereof for "breaking down." The object of my invention is to provide such a machine in which 20 vision is made for making such wall cuts horizontally at different elevations and also to make such wall cuts along upright planes, at the will of the operator.

In the accompanying drawings,

25 Figure 1 is a plan of a portion of a machine embodying my improvement;

Fig. 2 is a side elevation of the same machine, portions being broken away;

30 Fig. 3 is a front elevation of the same machine;

Fig. 4 is a section on the line, 4—4, of Fig. 2.

Referring to said drawings, A, is a truck having carrying wheels, 1, which rest on 35 track rails, R. B is a frame mounted upon the circular base, 2, of the truck, A, to turn like a turn-table on an upright axle, 3. Rollers, B', are attached to the frame, B, and rest on the circular base, 2. Above the 40 truck, the frame, B, has a level portion B² on which rests an electric motor, M, having its axis horizontal. On the forward end of the armature shaft M' of the motor is a bevel gear wheel, 5, which meshes with a 45 bevel gear wheel, 6, which is fixed around an upright shaft, 7. The upper end of said shaft rests in a bearing, 8, in a broad, horizontal, forward-directed arm, 9, and the lower end of said shaft rests in a bearing, 10, in a broad horizontal forward-directed arm, 50 11, the lower face of which almost touches the track rails, R.

Forward of the shaft 7, and at opposite sides of the extended axis of the wheel, 5, and the motor are two upright screw shafts, 55 12. Each screw shaft extends through a

bearing, 13, in the arm, 9, and into a bearing, 14, in the arm, 11. Each screw shaft, 12, projects above the arm, 9, and is there surrounded by and connected to a spur gear 60 wheel, 15, meshing with a spur gear wheel, 16, on a short shaft, 17, in an upright bearing, 18, in the arm, 9, midway between the screw shafts, 12. The hub of the gear wheel, 16, has lugs, 19. A wrench, 20, has a head, 21, to surround the upper end of the shaft, 17, and has a lug, 22, to extend downward between two lugs, 19. When in such position, the handle, 20, may be swung in a horizontal plane on the axis of the shaft, 17, 70 whereby the wheel, 16, and said shaft are rotated. The rotation of said wheel causes the rotation of the gear wheels, 15, the rotation of the latter being in the same direction. The screw threads on the shafts, 12, extend 75 in the same direction. Said shafts extend through a horizontal cross-head, 23, the latter being threaded to fit the threads of the shafts. Hence, the rotation of the wheel, 16, leads to the raising or lowering of the cross- 80 head, 23, for the latter must rise or fall when said shafts are turned.

A horizontal tool shaft, 24, extends through and has a bearing in the cross-head midway between the screw shafts. A bevel 85 gear wheel, 25, surrounds the shaft, 7, and is slidable lengthwise, but not rotatable thereon, a feather, 26, on the shaft, 7, preventing such rotation. Said wheel has a hub, 29, which has a circumferential channel, 27, which is entered by an arm, 28, extending rearward from the cross-head, 23, and around the hub. Thus said arm holds said hub against both downward and upward movement relative to the cross-head. 90 On the adjacent end of the shaft, 24, is a bevel gear wheel, 30, meshing with the gear wheel, 25. Since these two wheels are supported by the cross-head, they remain in mesh with each other, and since the wheel, 100 25, can slide along the length of the shaft, 7, but is held for rotation with said shaft, power is transmitted from the motor through the wheels, 5 and 6, the shaft, 7, the wheels, 25 and 30, to the tool shaft, 24, regardless of the elevation of the cross-head 105 and said shaft.

A rotary cutting tool, 31, adapted to cut while moving endwise and also while moving sidewise, is secured to the forward end 110 of the tool shaft, 24. The parts are preferably so proportioned as to bring the lower

portion of the cutting tool to the level of the bottom of the rails, R, when the cross-head, 23, is at its lower limit, and the slant of the tool shaft from the horizontal is made such 5 as to bring the lower face of the tool into the horizontal, in order that it may cut a level floor.

When the cross-head is in its lowest position, and the tool is being rotated, the machine may be pushed forward to drive the 10 tool forward into the wall. Then the frame, B, may be turned on the truck, A, to move the cutting tool horizontally. In this way the cut may be made as wide horizontally as 15 the horizontal range of the frame, B. If it is desired to make a horizontal cut at a higher level, the cross-head, 23, is raised to such level by turning the wheel, 16. An upright cut may be made by pushing the tool 20 endwise into the wall at a chosen elevation and then, without swinging the frame, A, raising or lowering the cross-head. If it is desired to make a diagonal cut, this may be done simultaneously rotating the cutting 25 tool, swinging the frame, B, and changing the elevation of the cross-head. The slant of such diagonal cut may be varied by varying the ratio between the lateral movement of the frame, B, and the upright movement 30 of the cross-head.

It is to be observed that the mechanism used for controlling the cross-head is low enough to permit the use of the machine in a mine having a low ceiling.

35 I claim as my invention,

1. In a machine of the nature described, the combination of a truck, a frame extending forward of and downward in front of the truck, the forward part of said frame 40 being movable horizontally and transversely to the travel line of the truck, upright screw shaft mechanism supported by the forward part of said frame, an approximately horizontal tool support supported by 45 said screw mechanism for up-and-down adjustment, an approximately horizontal tool on said support, and driving means located on the machine in operative relation with said tool for actuating the latter, substantially as described.

2. In a machine of the nature described, the combination of a truck, a frame extending forward of and downward in front of the truck, the forward part of said frame 55 being movable horizontally and transversely to the travel line of the truck, upright screw shaft mechanism supported by the forward part of said frame, an approximately horizontal tool support supported by said screw 60 mechanism for up-and-down adjustment, an approximately horizontal tool on said support, an upright shaft adjacent said support, gearing slideable on said shaft and in operative relation with said tool, and driving 65 means located on the machine in oper-

ative relation with said upright shaft for rotating the latter, substantially as described.

3. In a machine of the nature described, the combination of a truck, a frame extending forward of and downward in front of the truck, the forward part of said frame being movable horizontally and transversely to the travel line of the truck, upright screw shaft mechanism supported by the forward 75 part of said frame, an approximately horizontal tool support supported by said screw mechanism for up-and-down adjustment, an approximately horizontal tool on said support, an upright shaft adjacent said support, gearing slideable on said shaft and in operative relation with said tool, and a motor located on said frame in operative relation with said upright shaft for rotating the latter, substantially as described. 80

4. In a machine of the nature described, the combination of carrying wheels, an upper forward-directed arm, a lower forward-directed arm located in front of the carrying wheels, said arms being movable horizontally and transversely to the travel line of the truck, upright screw shaft mechanism extending from one of said arms to the other, an approximately horizontal tool support supported by said screw mechanism 90 for up-and-down adjustment, an approximately horizontal tool on said support, an upright shaft adjacent said support, gearing slideable on said shaft and in operative relation with said tool, and driving means 100 located on the machine in operative relation with said upright shaft for rotating the latter, substantially as described.

5. In a machine of the nature described, the combination of a truck, a frame mounted upon and extending forward of and downward in front of the truck and permitting lateral movement of said forward part, upright screw shaft mechanism on said forward part of said frame, an approximately 105 horizontal tool support supported by said screw mechanism for up-and-down adjustment, an approximately horizontal tool on said support, an upright shaft adjacent said support, gearing slideable on said shaft and in operative relation with said tool, and driving means located on the machine in operative relation with said upright shaft for rotating the latter, substantially as described. 110

6. In a machine of the nature described, the combination of a truck, a frame mounted upon and extending forward of and downward in front of the truck and permitting lateral movement of said forward part, upright screw shaft mechanism on said forward part of said frame, an approximately 115 horizontal tool support supported by said screw mechanism for up-and-down adjustment, an approximately horizontal tool on said support, an upright shaft adjacent said support, gearing slideable on said shaft and in operative relation with said tool, and driving means located on the machine in operative relation with said upright shaft for rotating the latter, substantially as described. 120

tool on said support, an upright shaft adjacent said support, gearing slidable on said shaft and in operative relation with said tool, and a motor located on said frame in operative relation with said upright shaft for rotating the latter, substantially as described.

7. In a machine of the nature described, the combination of a carrying portion, a frame supported upon said carrying portion to permit moving the forward part of said frame laterally, a tool shaft support movable up and down on said frame on an upright line, an upright shaft on said frame adjacent said support, gearing slidable on said shaft and in operative relation with said tool shaft, and driving means located on said frame in operative relation with said upright shaft for rotating the latter, substantially as described.

8. In a machine of the nature described, the combination of a carrying portion, a frame supported upon said carrying portion for turning on an upright axis and extending forward of and downward in front of said carrying portion, a tool shaft support located on the forward portion of said frame and movable up and down thereon on an

upright line, an upright shaft on said frame adjacent said support, gearing slidable on said shaft and in operative relation with said tool shaft, and driving means located on the machine in operative relation with said upright shaft for rotating the latter, substantially as described.

9. In a machine of the nature described, the combination of a carrying portion comprising carrying wheels, a frame supported upon and extending across the wheel base of said carrying portion to permit moving the forward part of said frame laterally, a tool shaft support movable up and down on the forward part of said frame on an upright line, an upright shaft on the forward part of said frame and adjacent said support, gearing slidable on said shaft and in operative relation with said tool shaft, and driving means located on the machine in operative relation with said upright shaft for rotating the latter, substantially as described.

In testimony whereof I have signed my name, in presence of two witnesses, this 12th day of August, in the year one thousand nine hundred and fifteen.

CYRUS S. OLDROYD.
